UNITED STATES PATENT OFFICE.

EDDY T. THOMAS, OF NEW YORK, N. Y., AND WHIPPLE V. PHILLIPS, OF PROVIDENCE, RHODE ISLAND, ASSIGNORS TO THE AMERICAN GAS TIP COMPANY, OF NEW YORK, N. Y.

GAS-BURNER TIP.

SPECIFICATION forming part of Letters Patent No. 366,528, dated July 12, 1887.

Application filed January 25, 1887. Serial No. 225,427. (No model.)

To all whom it may concern:

Be it known that we, EDDY T. THOMAS and WHIPPLE V. PHILLIPS, citizens of the United States, and residents of the city, county, and State of New York, and city and county of Providence, and State of Rhode Island, have invented a new and useful Improvement in Gas-Saving Tips, of which the following description, in connection with the accompanying drawings, is a specification, like letters on the drawings representing like parts.

The object of this invention consists in constructing a gas-burner tip with two longitudinal bisectional parts, so the gas is retarded in passing through, and so that the sections may be readily united.

The invention consists in forming a gas-burner tip with two longitudinal bisectional parts, having lugs and recesses on their 20 tangent faces, to prevent one section from slipping below the other, an enlarged chamber at the top of the tip, so that a broad flame will be given, and the lower end of the hole which forms a passage through the tip made smaller than the outlet at the top, so that the gas as it 25 comes from the main is checked and the direct force is turned against the walls of the chamber, substantially as described and claimed.

Figure 1 represents our improved bisectional tip. Fig. 2 shows the face and concave of one of the sections of Fig. 1. Fig. 3 shows the lower end of the tip on line xx , Fig. 1. Fig. 4 shows the tip on line xx , Fig. 2.

A, Fig. 1, represents one of our improved tips, having bisectional parts ee divided on line c , and having slot m , formed at the time of striking or molding the parts by offsetting the material on one or both of the contiguous faces, preferably on both, as in manufacturing 35 both parts will be made alike, so they will be interchangeable, and thus save the annoyance of assorting and selecting the right parts to fit. We also save the expense of two sets of dies or molds. We are enabled to do this by 40 forming one-half of the slot m on each section; also one lug, b' , and one recess, b , on each, so when two made alike are turned face to face the lug b' fits into the recess b of the other section. By the aid of these lugs one section is

prevented from slipping below the other as 50 they are pressed into the barrel, which holds them together and prevents the gas from escaping between the faces.

We intend to manufacture these tips from sheet metal, and in so doing we shall form a 55 concave head, o , Fig. 2, which will be larger than the diameter of the passage d . By this we are enabled to produce a tip which will give a broad round flame.

That the direct flow of the gas in its course 60 through the tip may be changed, and consequently a lighter pressure obtained at the outlet of the tip, we form a flange, i , on the lower end of the tip, as shown in Fig. 2, in which we make a hole, t , as shown in Fig. 3, through 65 which the gas must pass in its course to the slot m , which is of larger capacity than the hole t . That we may further check the flow of gas, the holes t in the bisectional parts ee , Fig. 3, are formed at an inclination to the bottom of the tip, as shown in Fig. 2. This causes the gas to strike the chamber d at an angle, (shown by line xx , Fig. 2,) forcing the gas to take a zigzag course as it passes through.

As both of the bisectional parts ee , forming 75 the tip A, are made by one die, and the hole t is on an angle, two openings are made into the chamber d when the sections are put face to face. This diverts the flow of gas and forces it against the opposite walls of the chamber d , 80 destroying any direct flow of gas through the tip as it comes from the main. By this plan we are enabled to save a large per cent. of the gas, and as a more complete combustion takes place a better light is produced.

The capacity of the holes t or their equivalents should be smaller than the slot m .

We are aware that regulators have been used, but not with the tips.

Having thus fully described our invention, 90 what we claim as new, and desire to secure by Letters Patent, is—

1. The gas-burner tip A, provided with longitudinal bisectional parts ee , each section being provided with lug b' and recess b on the 95 contiguous faces, so the sections will be interchangeable, as and for the purpose specified.

2. A longitudinal bisectional gas-burner tip,

A, provided with parts *e e*, lug *b'* and recess *b*, flange *i*, and hole *t* on their contiguous faces, so the sections will be interchangeable, as and for the purpose specified.

3. A longitudinal bisectional gas-burner tip, A, provided with parts *e e*, having the chamber *d*, enlarged at *o*, lug *b'* and recess *b* on their contiguous faces, so the sections will be interchangeable, as and for the purpose specified.

In testimony that we claim the foregoing as our invention we have signed our names, in presence of two witnesses, this 30th day of November, 1886.

EDDY T. THOMAS.
WHIPPLE V. PHILLIPS.
